(No Model.)

A. H. JOHNSON.

INTERLOCKING DEVICE FOR RAILWAY SWITCHES AND SIGNALS.

No. 392,734.

Patented Nov. 13, 1888.

UNITED STATES PATENT OFFICE.

ARTHUR H. JOHNSON, OF JERSEY CITY, NEW JERSEY.

INTERLOCKING DEVICE FOR RAILWAY SWITCHES AND SIGNALS.

SPECIFICATION forming part of Letters Patent No. 392,734, dated November 13, 1888.

Application filed August 17, 1888. Serial No. 283,016. (No model.)

To all whom it may concern:

Be it known that I, ARTHUR H. JOHNSON, of Jersey City, in the county of Hudson and State of New Jersey, have invented a new and useful Improvement in Mechanism for Interlocking Railway Switches and Signals, of which the following is a specification, reference being had to the accompanying drawings.

This invention relates to that form of interlocking between switch and signal levers known as "special locking" or "conditional." This form of locking differs from the ordinary locking, inasmuch as the locking or releasing of one lever or levers by another lever or levers is conditional upon the position of a third or other lever or levers.

Figure 1 is a plan of a very simple example of a system of interlocking tappets and locks illustrating my invention. Fig. 2 represents a section at right angles to Fig. 1 in the line *xx*. Fig. 3 is a face view, and Fig. 4 a side view, of one of the tappets and its appurtenances illustrating a modification of my invention. Fig. 5 is a face view, and Fig. 6 a side view, of a tappet illustrating another modification. Fig. 7 is a face view of one of the slides or sliding sections of a tappet illustrating another modification.

Similar letters of reference designate corresponding parts in all the figures.

A' A² A³ A⁴, Fig. 1, designate four tappets, which—except that *A² A³* are fitted with transverse slides or sliding sections *B' B² B³ B⁴*—are like those in common use in interlocking apparatus. The said tappets are represented arranged parallel with each other and fitted between projections or guides *c c* on a bed-plate, *C*, in the usual manner, and are intended to be connected in the usual manner at *d d* with the operating-levers.

D' D² D³ D⁴ D⁵ D⁶ designate miter dogs or locks such as are commonly employed in interlocking apparatus, arranged to slide between the projections or guides *c c* of the plate *C* in a direction transverse to the movement of the tappets for the purpose of engaging with or disengaging from the V-shaped notches *a a* or *b b* in the tappets. The notches *a a* (shown in the tappets *A' A⁴*) are like those in tappets commonly used.

The slides or sliding tappet-sections *B' B² B³ B⁴* are what constitute the principal feature of

my invention. They consist of plates each having in one edge one or more notches, *b b*, which, like the notches *a a*, correspond in form with the ends of the miter dogs or locks, the number of said notches being according to the particular special locking to be performed. These slides or sliding sections are fitted to transverse slideways *e e* in their respective tappets. 55 The parts of the tappets on which the sliding sections are applied within the slideways are represented as made narrower than the other parts. In the example shown in Figs. 1 and 2 the slideways *e e* are made within the tappets themselves and the sliding sections are fitted to them with rabbets. In the example shown in Figs. 3 and 4 the slideways are formed by gibs bolted to the face of the tappet. In the example shown in Figs. 5 and 6 the tappet consists of a narrow bar, *f*, having secured firmly to it by rivets or bolts pieces *g g*, which form the slideways *e* and the heads *d*. In the example shown in Fig. 7 the sliding section is shown constructed with two transverse slots, 60 75 *h*, to slide on pins *i* in the tappet.

In Fig. 1 two examples of special locking are illustrated. In this figure the tappets are shown in their home position in full outline and in their reversed positions in dotted outline. In the first of these examples the tappet *A³* locks *A²* back and front when *A'* and *A⁴* are both reversed, but not when either *A'* or *A⁴* is home. The sliding section *B²* of the tappet *A³* has a notch, *b*, which is opposite the miter of the dog or lock *D²* when *A³* is in its home position. Now, it will be understood by reference to Fig. 1 that when the tappet *A³* is reversed *A²* will not be locked either back or front if both or either *A⁴* or *A'* is in 80 the position shown, because, although the miter at the left hand of the dog *D²* will be made to coincide with one of the notches in the slide *B'* the tappet *A²* is free to be moved because of the side play allowed to the sliding sections 85 *B'* and *B²*. If, however, both the tappets *A'* and *A⁴* are reversed, then the dogs *D'* and *D³* will be made to abut with the sliding sections *B'* and *B²*, as shown in dotted outline in Fig. 1, so that when *A³* is reversed and the left-hand 90 end of the dog *D²* is made to coincide with either of the notches in the sliding section *B'* the tappet *A²* will be held in that position with its operating-lever in corresponding po- 95 100

sition, because all side movement of D', B', and D² is checked. In the other example the tappet A⁴ locks A' only when A² is over or reversed and A³ is home. If the tappet A², 5 which is fitted with the sliding section B³, be reversed, and the tappet A³ carrying the slide B⁴ remain in its normal position, then D⁴ B³ D⁵ B⁴ D⁶ will form or operate in combination with each other to form between the tappets A' and 10 A' a continuous dog of such length that if the tappet A⁴ be reversed said continuous, or, as it may be termed, the "combination," dog, will have its miter, which consists of the right-hand extremity of D⁶, forced out of the corresponding notch a in the tappet A⁴ and its miter formed by the left-hand extremity of D⁴ forced into the corresponding notch a in the tappet A', thus securely holding the last- 15 mentioned tappet in the normal or home position; but this locking of A' by A⁴ is conditional upon A² being reversed and A³ being home, as it will be readily seen that if the 20

notch in either sliding section B³ or B⁴ is opposite the dog D⁴ or D⁶, then there is a sufficient lost stroke in the combination-dog to 25 permit A' to be reversed at the same time as A⁴.

When the interlocked tappets are not adjacent, as shown in Fig. 1, but remote from each other, I propose to employ the ordinary 30 connecting-rods to transmit the action of one dog to another.

What I claim as my invention, and desire to secure by Letters Patent, is—

The combination, with the tappets of an interlocking switch or signal operating apparatus and dogs between the said tappets for locking them together, of slides or sliding sections fitted to said tappets for operating said dogs, substantially as herein described.

ARTHUR H. JOHNSON.
